UNITED STATES PATENT OFFICE.

CHARLES W. MERRILL, OF ALAMEDA, CALIFORNIA.

HYDRAULIC CLASSIFIER.

SPECIFICATION forming part of Letters Patent No. 728,487, dated May 19, 1903.

Application filed May 12, 1902. Serial No. 106,914. (No model.)

To all whom it may concern:

Be it known that I, CHARLES W. MERRILL, a citizen of the United States, residing at Alameda, county of Alameda, State of California, have invented an Improvement in Hydraulic Classifiers; and I hereby declare the following to be a full, clear, and exact description of the same.

My invention relates to an apparatus which is especially designed for separating the heavier or coarser from the lighter or finer components found in tailings of ores or other valuable products, these separations being technically known as "concentrating" and **15** "classifying."

It consists of the parts and the constructions and combinations of parts hereinafter described and claimed.

Referring to the accompanying drawings, **20** Figure 1 is a vertical sectional view of the device on the line *x x* of Fig. 2. Fig. 2 is a horizontal section on the line *y y* of Fig. 1.

In the methods which have been employed for separating or classifying the substances **25** found in tailings and the like a conical, pyramidal, or similarly-shaped hopper has been employed, into the top of which the pulp has been delivered, and water is admitted directly into the lower part to flow upwardly **30** through the said hopper with the object of causing the lighter material to be constantly raised and discharged over the upper edges of the hopper, while the heavier sand passes out through a discharge-opening at the bottom. This apparatus is open to objection by **35** reason of a disturbance created by the current of water admitted, which prevents the proper separation of the material.

In my invention I have shown a supplementary cone A, having a discharge-opening **40** 2 at the apex, which apex is presented downwardly. Around the upper part or base of the cone is an annular closed chamber 3, having an inlet, as at 4, through which water may be admitted within this chamber. In the bottom **45** of this annular chamber is an annular channel 5, opening from the chamber into the upper and larger part of the receiver and near

the inner periphery thereof. Through the center of the annular chamber is a passage **50** 6, extending upwardly and having its axis approximately coincident with the axis of the discharge-opening at the bottom of the cone. Through this passage connection is made with the supply and overflow **55** hopper 7, which is located above and may be secured to the top of this device by being screwed into it or otherwise.

The pulp containing the sulfurets, slimes, or other material of different sizes and specific gravity which are to be separated is delivered into the upper part of the supply-hopper 7 and mingled with such a quantity of water that it will be sufficiently thin to flow freely. A current of water being admitted **60** through the passage 4 into the annular chamber will be discharged downwardly through the annular channel 5 around the periphery of the conical chamber A. This water replaces the slimier water, which would otherwise be carried down and out with the sand or heavier components. The heavier sand will flow downwardly through the opening and through the lower cone, passing out through the discharge 2 at the bottom. The effect of **70** this structure is to admit the water in a continuous surrounding sheet, so that it converges from all sides toward the center.

Having thus described my invention, what I claim, and desire to secure by Letters Patent, is—

1. A hydraulic classifier consisting of a closed downwardly-convergent receiver, with a central supply-opening at the top and a discharge-opening in line therewith at the bottom, a closed clear-water chamber concentric with and separated from the upper central opening, said chamber having a bottom provided near the inner wall of the upper and larger end of the receiver, with a continuous **85** channel opening downwardly into the receiver.

2. A hydraulic classifier consisting of a closed downwardly-convergent receiver with a central discharge-opening at the bottom, a **90** centrally-located supply-opening at the top,

a water-chamber surrounding said opening and having a side supply-opening and a bottom slotted to form a continuous channel opening into the receiver near the inner periphery of said receiver, and a source of supply connecting with the opening at the top of the receiver.

In witness whereof I have hereunto set my hand.

CHARLES W. MERRILL.
